BASEBOARD TYPE ELECTRIC WALL HEATER

Theodore W. Glynn, Kingsport, Tenn., assignor to Blue Ridge Glass Corporation, Kingsport, Tenn., a corporation of New York

Application October 26, 1954, Serial No. 464,699

10 Claims. (Cl. 219—34)

This invention relates to electric heaters designed to be mounted in the baseboards of rooms, and more particularly to such a heater in which the resistance element is mounted on a glass plate.

It is among the objects of this invention to provide a baseboard type electric wall heater which can have high wattage for its size, which is low enough to fit in most baseboards, which is relatively simple and inexpensive in construction, and which is strong and durable.

In accordance with this invention, the frame of the heater is formed principally from a small I-beam of any desired length that has upper and lower flanges connected by a vertical web. A vertical glass heater plate is mounted between the flanges in front of the web and is provided on its rear surface with an electric resistance heating element. Behind the web of the beam is a heat-barrier panel that is mounted between the flanges of the beam. Preferably, the panel has a body of thermal insulating material and a bright front face to reflect heat forward. The glass heater plate may be held in place by facing members engaging the front surface of its ends, and by resilient members engaging the rear surface of the ends. It is preferred to mount a resilient sealing strip between the top of the heat-barrier panel and the adjacent flange of the I-beam, the strip projecting behind the beam to engage the wall in order to seal the space between the flange and wall so that streaking of the wall by rising air currents will be minimized.

The preferred embodiment of the invention is illustrated in the accompanying drawings, in which:

Fig. 1 is a front view of my baseboard heater mounted in a wall;

Fig. 2 is an enlarged front view of the heater with the central portion broken away and with one end of the heater plate broken away;

Fig. 3 is a horizontal section taken on the line III—III of Fig. 2; and

Fig. 4 is a vertical section taken on the line IV—IV of Fig. 3.

Referring to the drawings, the frame of the heater is constructed from a small I-beam 1, such as a seven inch junior beam 2 to the opposite ends of which metal plates are welded. These plates are flush with the front and top of the beam, but project below it about three-fourths of an inch to raise the bottom of the beam to the top of the usual quarter round around the wall of a room. The frame can be made any desired length by simply using an I-beam section of that length. As shown in Fig. 1, the frame is adapted to be set into a baseboard 3 in a gap cut therein, and the quarter round 4 that otherwise would extend along the baseboard where the frame is located is moved forward and secured to the floor at the base of the frame. Another quarter round 6 may be fastened to the wall 7 along the top of the frame to provide a finished appearance.

Mounted in the front of the frame; that is, between the upper and lower flanges in front of its web 8, is a vertical

glass heater plate 9. Applied to the back of this plate in a well-known manner is an electrical resistance heating element 10 (Fig. 3) in the form of an aluminum or aluminum alloy strip. The height of the plate is less than the distance between the beam flanges, and the plate is centered between them by metal brackets 11 so that air can circulate up between the plate and the web of the beam. There is a bracket 11 at each corner of the plate and it has a horizontal portion that extends away from web 8 forward across the adjoining flange and adjacent edge of the heater plate. Extending vertically from the back of each bracket towards the other bracket is a lug 12, through which screws 13 extend that fasten the bracket to the web. In the front of each bracket there is a recess in which there is a resilient block 14 made of silicone or neoprene or other suitable rubber-like material. These blocks at the four corners of the glass plate engage its rear surface and space it from the brackets. The plate is held in position and pressed tightly against the resilient blocks to compress them slightly, by means of vertical facing strips 16 which extend across the front of the plate at its opposite ends. The ends of the strips overlie the front edges of the beam flanges. The strips are removably mounted in place by means of screws 17 that extend into the forwardly projecting portions of the brackets above and below the glass plate.

The wires 18 that connect the electric heating element into an electric circuit extend back through holes in the web of the beam near its opposite ends. Behind one of these holes 19 (Fig. 2) there is a rectangular metal plate 21 that has one edge welded to a vertical angle bar 22 (Fig. 3) which is welded to the adjacent end plate 2 of the frame. A similar angle bar 23 is welded to the end plate at the opposite end of the frame. Secured to the back of the rectangular plate is a junction box 24, and the plate is provided with a circular opening giving access to the box. This opening normally is closed by a circular lid 26. The web in front of this lid is provided with another circular opening that normally is closed by a square cover 27. The wires 18 from the heating element can be connected with an outside circuit in the junction box.

To prevent too much heat from the heater plate being dissipated back of the heater, where it may overheat the wall, a heat barrier is placed in the back of the frame. This barrier is a panel 30 disposed between the upper and lower flanges of the I-beam. The panel is made of thermal insulating material, such as Rocklath, and it is held in place by screws 31 extending through it and into the angle bars 22 and 23 at the opposite ends of the frame. The panel is provided with an opening through which the junction box extends. The efficiency of the heater is improved if the front surface of the panel has a brief reflecting surface 32 (Fig. 4). One way of producing such a surface is to cover the panel with aluminum foil.

To prevent heat from rising between the back of the heater and the wall, which would greatly increase the likelihood of wall streaking, a resilient sealing strip 33 projects from the back of the frame at the top. This strip extends the full distance between the end plates of the frame and preferably is provided in its bottom with a recess that receives the top of the insulating panel to hold the strip in place against the upper flange of the frame. When the heater is mounted in place the back of the sealing strip is pressed against the wall as shown in Fig. 4.

According to the provisions of the patent statutes, I have explained the principle of my invention and have illustrated and described what I now consider to represent its best embodiment. However, I desire to have it understood that, within the scope of the appended claims,

the invention may be practiced otherwise than as specifically illustrated and described.

I claim:

1. A baseboard type electric wall heater, comprising an I-beam having upper and lower flanges connected by a vertical web, a vertical glass heater plate mounted between said flanges in front of said web and provided on its rear surface with an electrical resistance heating element, and a heat barrier panel mounted between said flanges behind the web.

2. A heater in accordance with claim 1, including resilient members engaging the rear surface of the ends of said plate, and facing members engaging the front surface of the plate ends and pressing the plate against said resilient members.

3. A heater in accordance with claim 1, including brackets secured to the I-beam between the corners of said plate and said web, resilient blocks supported by the brackets in engagement with the rear surface of the plate, and vertical facing strips engaging the front surface of the ends of the plate and secured to said brackets to press the plate against said blocks.

4. A heater in accordance with claim 1, in which said panel has a body made of thermal insulating material and a bright reflecting front surface.

5. A heater in accordance with claim 1, including vertical end plates covering the opposite ends of said I-beam and projecting below it to space it from the floor.

6. A heater in accordance with claim 1, including elec-

tric wires connected with said heating element, said web being provided with holes through which the wires extend.

7. A heater in accordance with claim 1, including a resilient sealing strip mounted between the top of said panel and the adjacent flange of the I-beam, said strip projecting behind the I-beam and being adapted to engage a wall to seal the space between said flange and wall.

8. A baseboard type electric wall heater, comprising 10 an I-beam having upper and lower flanges connected by a vertical web, a vertical glass heater plate mounted between said flanges in front of said web and provided on its rear surface with an electrical resistance heating element, the plate being spaced from said flanges, brackets 15 secured to said web at the corners of said plate and having portions projecting above and below the plate, vertical facing strips extending across the front of the ends of the plate, fastening members securing said strips to the front of said projecting portions of the brackets, and resilient members compressed between the back of the plate and said brackets and pressing the plate against said strips.

9. A heater in accordance with claim 8, in which said 20 resilient members are rubber-like blocks mounted in recesses in said brackets.

10. A heater in accordance with claim 8, in which said 25 projecting portions of the lower brackets extend forward beneath the bottom of said plate and support it.
